CLEANING DEVICE FOR WINDING MACHINES
AND THE LIKE

George B. McCallum, Northampton, Mass.

Application June 14, 1938, Serial No. 213,648

4 Claims. (Cl. 28—68)

My invention relates to a device for cleaning threads or yarns such for example as the silk threads used in the manufacture of hosiery.

Various arrangements of cleaning brushes and slotted members have been proposed, as well as blowers and suction devices, but as far as I am aware none of these has been satisfactory in actual practice, particularly for threads running at high speed. The purpose of these devices is to remove from the thread lint, dust, and other foreign particles which collect on the thread. The usual practice of passing the thread through slotted members causes the lint, dust, etc., to collect at the mouth of the slot, from which it is supposed to be removed periodically by an attendant, but at irregular intervals the accumulation of foreign material or a part thereof will pass through the slot opening before removal and will be wound up on the spool. These accumulations later appearing in the finished product cause serious defects. It has been customary in the past to employ blowers in an effort to keep the thread free of lint and dust, but such devices by scattering the lint and dust contaminates the air and the scattered material eventually settles on the yarn or thread at other points. It has also been proposed to install suction devices at various points in an attempt to remove the lint and dust from the air before it reaches the thread; but such devices are only partially successful, due partially to the fact that at least some of the lint is borne by the thread and not by the air, and they involve a substantial operating expense in maintaining the vacuum over the relatively large areas necessarily covered if the system is to be even appreciably effective.

The usual apertured and slotted members are in themselves reasonably effective in collecting the lint and dust but periodic passage of the accumulations through these members previously mentioned very materially decreases their utility in practice. In an effort to overcome this, one proposal has been to make the slotted member rigid and with sharp edges so that the thread is cut or broken when an accumulation enters the slot but the necessity of tying the broken thread is objectionable. It has also been proposed to apply a suction member at a point beyond the slotted or other cleaner member for the purpose of attempting to remove the accumulations after they have passed the slot. The presence of these accumulations, however, shows that they have already attached themselves to the thread with sufficient tenacity to be drawn through the slot, and they are travelling at high speed; and the

vacuum, unless prohibitively high, is ineffective to dislodge them as they dart by.

It is the object of my invention to provide a cleaning device which overcomes the above-mentioned deficiencies of the prior art devices and which is reliable and economical in operation.

I have found that by combining with a vacuum nozzle a suitably shaped arresting member, accumulations passing the cleaning slot can be effectively and economically removed from the thread. This arresting member may be one of the usual thread guides if the latter is of suitable shape.

In the accompanying drawing which illustrates one embodiment of my invention, 15

Fig. 1 is a side elevational view of a device constructed according to my invention;

Fig. 2 is a front elevational view of the structure shown in Fig. 1;

Fig. 3 is a detail view of the arresting and the suction member looking in the direction of the arrows in Fig. 1; and

Fig. 4 is a detail sectional view substantially on line 4—4 of Fig. 2.

Referring to the drawing, 10 designates a suitable frame member of the spooling machine to which the cleaning devices may be conveniently attached. A bracket 11 is secured as by screws 12 to member 10. Bracket 11 supports a conventional porcelain thread guide 14 by which the thread is guided to a slotted cleaning plate 15 of any conventional type. Slotted member 15, which may be made up of one or more pieces, serves to collect the lint and dust from the thread, this material collecting at the point 16 in the manner previously described. From the plate 15 the thread passes over a guide 17, preferably of porcelain, which is of a form to act as an arresting or restraining member for the lint, and thence to the spool diagrammatically shown at 18. As shown, 40 the member 17 is provided with a thread receiving channel generally indicated at 20, the adjacent top surfaces being grooved as at 21 to receive the ends of a spring clip 22 by which the member is held to frame member 10. The bottom of 45 member 17 is formed with a rectangular notch or channel as at 23 to engage and seat on a corner of frame member 10. Spring clip 22 is secured in any suitable manner, not shown, to the frame member 10.

A suction nozzle 25 is supported adjacent member 17 by a strap 26 secured to frame member 10 and is connected by pipe 27 to any suitable source of suction, not shown.

As best shown in Figs. 3 and 4, the entrance 55

and exit to channel 20 are flared, as indicated at 28 and 29, and the opening of nozzle 25, which is elongated, as by flattening the end portion of a circular pipe, is positioned closely adjacent 5 the exit or discharge side of the channel. This arrangement of the suction nozzle is important and one satisfactory relation shown in the drawing is best indicated in Fig. 4. In the latter figure it will be seen that the "floor" 30 of channel 20 is curved in the plane of thread travel and that the orifice of the nozzle 25 overlies the thread, shown at t, over a zone including a portion in which the thread is in contact with the floor of the channel and a portion just after it 10 has separated from the floor because of the curvature of the latter.

It is difficult to describe exactly what takes place in the removal of the accumulation by the suction nozzle. Apparently as an accumulation 20 passes through the cleaning slot it is suddenly arrested or at least materially checked as the floor of the member 17 is encountered, and its hold on the thread is in part at least broken. At the same time the free ends of the lint pieces 25 are drawn into the nozzle, further loosening the particles which make up the accumulation. As the accumulation works along the channel more and more pieces are detached with a further disintegration of the accumulation, probably aided 30 by an unwinding action as the lint particles are drawn into the nozzle which tends to roll or partially rotate the thread or the accumulation or both. As the accumulation reaches the point where the thread leaves the floor of the groove 35 it is disintegrated to a degree that the remaining portion is easily and completely removed by the suction. The above is a "slow motion" description of what in fact takes place rapidly, and without perceptible pause, in the advance of 40 the accumulation. Whatever the nature of the action which takes place, the arrangement in practice has been surprisingly efficient in actual practice and has effected a very substantial saving by practically eliminating the loss of finished articles due to the presence in the product of lint 45 and similar accumulations. The device is easily and cheaply installed on machines already equipped with conventional cleaning slots requiring at most, in addition to the vacuum nozzle, the substitution of a suitably shaped thread guide if the guide beyond the cleaning slot is not of a form to properly cooperate with the suction nozzle as described. In other instances the shape of the suction orifice, or its location 50

can be made to conform to a particular guide or all three may be changed as conditions require.

What I claim is :

1. A thread cleaning device which comprises in combination with a member for accumulating 5 lint and other foreign material from the thread as the latter passes through the member, a restraining member spaced from the first-mentioned member in the direction of thread travel and a vacuum nozzle positioned closely adjacent 10 the restraining member to disrupt and remove from the thread accumulations of material passing through the first-named member as the movement of the accumulations is checked by the restraining member.

2. A thread cleaning device for a thread winder which comprises in combination with a member for accumulating lint and other foreign material from the thread as the latter passes through the member, a restraining member 20 spaced from the first-named member in the direction of thread travel and a vacuum nozzle positioned closely adjacent the restraining member 25 at the discharge side thereof and acting on the thread while on and just after it leaves the surface of the restraining member, the vacuum nozzle being positioned to permit direct passage of the thread from it to the winder without the interposition of other guides upon 30 which lint might accumulate.

3. A thread cleaning device which comprises a guide member having a smooth, curved, thread-supporting floor against which accumulations of lint on the thread will be restrained, and a vacuum nozzle positioned adjacent the 35 portion of thread supported by said floor, the nozzle having an effective extent including the point where the thread leaves the guide.

4. A thread cleaning device for a thread winder which comprises a guide member having a smooth, curved, thread-supporting floor against which accumulations of lint on the thread will be restrained, and a vacuum nozzle positioned adjacent the portion of thread supported by said floor, the nozzle having an effective extent including the point where the thread leaves the guide, the guide member and vacuum nozzle being so arranged with respect to the thread winder as to permit direct passage of the thread from the nozzle to the winder 40 without interposition of other guides upon which 45 lint might accumulate.

GEORGE B. McCALLUM.
